(57) **CLAIM**

The ornamental design for a stepped platform toy brick as shown and described.

DESCRIPTION

FIG. 1 is a top perspective view of a stepped platform toy brick.

FIG. 2 is a second, top perspective view of the stepped platform toy brick.

FIG. 3 is a third, top perspective view of the stepped platform toy brick.

FIG. 4 is a bottom perspective view of the stepped platform toy brick.

FIG. 5 is a second, bottom perspective view of the stepped platform toy brick.

FIG. 6 is a third, bottom perspective view of the stepped platform toy brick.

FIG. 7 is a side plan view of the stepped platform toy brick.

FIG. 8 is a second, side plan view of the stepped platform toy brick.

FIG. 9 is a front plan view of the stepped platform toy brick.

FIG. 10 is a back plan view of the stepped platform toy brick.

FIG. 11 is a top plan view of the stepped platform toy brick.

FIG. 12 is a bottom plan view of the stepped platform toy brick.

FIG. 13 is a top perspective view of a second embodiment of the stepped platform toy brick.

FIG. 14 is a second, top perspective view of the second embodiment of the stepped platform toy brick.

FIG. 15 is a third, top perspective view of the second embodiment of the stepped platform toy brick.

FIG. 16 is a bottom perspective view of the second embodiment of the stepped platform toy brick.

FIG. 17 is a second, bottom perspective view of the second embodiment of the stepped platform toy brick.

FIG. 18 is a third, bottom perspective view of the second embodiment of the stepped platform toy brick.

FIG. 19 is a side plan view of the second embodiment of the stepped platform toy brick.

FIG. 20 is a second, side plan view of the second embodiment of the stepped platform toy brick.

FIG. 21 is a front plan view of the second embodiment of the stepped platform toy brick.

FIG. 22 is a back plan view of the second embodiment of the stepped platform toy brick.

FIG. 23 is a top plan view of the second embodiment of the stepped platform toy brick; and,

FIG. 24 is a bottom plan view of the second embodiment of the stepped platform toy brick.

(Continued)

The broken lines in the figures show features of the stepped platform toy brick that form no part of the claimed design.
